UNITED STATES PATENT OFFICE.

ADAM NICKEL, OF NEW YORK, N. Y.

PIANO-DAMPER.

SPECIFICATION forming part of Letters Patent No. 595,458, dated December 14, 1897.

Application filed July 23, 1897. Serial No. 645,684. (No model.)

To all whom it may concern:

Be it known that I, ADAM NICKEL, of New York city, county and State of New York, have invented an Improved Piano-Damper, of 5 which the following is a specification.

This invention relates to a piano-damper of novel construction, and has for its object more particularly to provide means for adjusting the tension of the damper-spring in a 10 simple and effective manner.

In the accompanying drawings, Figure 1 is a side view of my improved piano-damper; Fig. 2, a longitudinal section on line 2 2, Fig. 1; Fig. 3, a longitudinal section on line 3 3, 15 Fig. 2; and Fig. 4, a transverse section on line 4 4, Fig. 1.

The letter *a* represents the damper-lever, pivoted to damper-flange *b* by pivot *b'*, the damper-flange being in turn adapted to be attached to the action-rail *c*, all as usual. The 20 damper-spring *d* is coiled around the pivot *b'*, and in order to admit the coils of such spring the damper-lever *a* is provided with a groove *a'* around such pivot. The lower forwardly-bent arm of spring *d* enters a groove *b*² in the lower face of the damper-flange *b*, and is engaged by a set-screw *e*, that passes through said flange preferably in a slightly-slanting direction and projects across the groove *b*².

25 In order to effect the engagement between spring *d* and screw *e*, the screw has a neck or

contracted section *e'* near its lower end and within groove *b*², which forms a seat for the spring. By providing the screw with this contracted neck I avoid the necessity of enlarging the lower end of the screw to form a 35 head which would have to be countersunk, and I can, moreover, place the screw nearer to the edge of the flange *b*.

The spring *d* bears permanently against the 40 lower side of the screw-neck *e'*. To increase the tension of the spring, the screw *e* is slightly raised by means of a screw-driver to draw the spring upward, while to decrease such tension the screw is slightly lowered, as will be 45 readily understood.

What I claim is—

A piano-damper provided with a grooved lever, a grooved damper-flange pivotally connected thereto, a spring engaging the lever 50 and having a forwardly-extending arm that projects into the groove of the flange, and a regulating-screw passing through the flange and having a contracted neck to receive the spring-arm, which bears permanently against 55 the lower side of such neck, substantially as specified.

ADAM NICKEL.
